UNITED STATES PATENT OFFICE.

DORA S. DAILY, OF SAN FRANCISCO, CALIFORNIA.

HOOK AND EYE.

SPECIFICATION forming part of Letters Patent No. 710,671, dated October 7, 1902.

Application filed January 16, 1902. Serial No. 89,977. (No model.)

To all whom it may concern:

Be it known that I, DORA S. DAILY, a citizen of the United States, residing in the city and county of San Francisco, State of California, 5 have invented an Improvement in Hooks and Eyes; and I hereby declare the following to be a full, clear, and exact description of the same.

My invention relates to an appliance to be 10 used for the closing of openings in clothing.

The object of the invention is to provide a device which is designed for fastening in a neat and secure manner the overlapping portions of garments, such as the side portions 15 under the arms and over the shoulders in waists and the back openings or side openings in skirts, whereby the fastening may be made without injury to the material upon which it is used, at the same time conducing 20 to security, neatness, availability, and protection.

My invention consists of an arrangement by which the hook and eye are brought together by means of a spring or snap.

25 The eye has a solid back, thus protecting the most delicate material from the wear incidental upon the pressing of the hook against the cloth, as in the case of all existing side-fastening hooks and eyes. The back of the 30 eye is provided with a raised or embossed tongue running lengthwise through the center.

The hook has a rounded split top, which top is split through the center and an elongated oval opening made in it in such a manner as to give the double tongue thereby created the action of a spring when the hook is fitted into the eye and pressed over the raised tongue of the eye.

40 Perforations are provided for attaching the hook and eye to the material by means of sewing in such a manner as to absolutely conceal the hook and eye when the garment is closed.

45 My invention comprises details of construction which will be more fully explained by reference to the accompanying drawings.

Figure 1 is a bottom plan of my improved hook attached to a piece of fabric. Fig. 2 is 50 a top plan of my improved eye attached to a piece of fabric. Fig. 3 is a side elevation, sectional through the fabric, of my improved

hook and eye locked as they appear when in actual use. Fig. 4 is a rear end view in elevation of my improved eye, showing slot or 55 opening through which the bill or tongue of my hook engages the eye. Fig. 5 is a top plan of the blank of my improved eye, showing same as it is stamped out prior to forming into shape. Fig. 6 is a top plan showing 60 the blank of my improved hook, showing same as it is stamped out prior to forming into shape.

Similar characters of reference refer to similar parts.

65 The letter A represents my improved hook formed of stamped metal sheet, as shown in Fig. 6, having the spoon-bill or hook part a, perforated with an elongated oval opening a' about its center and split outwardly, as shown 70 at 1, forming a double tongue at the oval end of hook proper. (Fully shown in Fig. 6.) This tongue or bill a is bent backward toward the end of base-piece b and on the same plane as the base, its rounding split end a' being 75 further slightly curved inward toward the base, as shown in Fig. 3. The hook-base b has suitable perforations b' b' for attaching it to the fabric.

80 The letter B represents my improved eye or female member stamped out of one single metallic sheet in the form as fully shown in Fig. 5. This eye has a base c, in which a longitudinal tongue c' is cut by being left within the partly-cut longitudinal opening d in said 85 base. At one end this member has a semi-circular-shaped opening d', which in stamping out leaves the protecting edge e. The eye is formed from this blank by bending upward and backward toward the end of its 90 base c the edge e at a line with the straight base of the opening d'. (Shown in Fig. 5 by the figures 2 3 and fully formed, as in Figs. 3 and 4.) The tongue c' in the base c is given an upward curve, forming a hump or stop 95 which engages within the oval opening a' of the hook-bill when locking both in position and fully shown in Fig. 3. The base c of the eye member has similar suitable perforations f' f' to those in the base of the hook for fastening to the fabric.

100 By the peculiar construction of both my improved hook and eye it will be seen that once locked, as shown in Fig. 3, it will be impossi-

ble for them to come apart, owing to the opening in the bill or hook engaging over the hump made by the bent tongue in the center of the base of the eye member, and they can 5 only be separated by deliberate force or by unhooking in the proper manner—viz., by pressing the edge *g* of the overlying fabric, thereby raising the inner or bill end of the hook, so that it can be easily pulled over the 10 hump in the eye at the same time that the outer edge *h* of the fabric carrying the eye is pushed forward, allowing the two members to be easily separated from each other.

Having thus described my invention, what 15 I claim as new, and desire to secure by Letters Patent, is—

In combination with an eye member constructed from one single sheet-metal piece, having a bent open portion at one end and a bent spring-like tongue projecting from its 20 base, a hook member also constructed from a single piece stamped from sheet metal, having a spoon-like bill or tongue centrally perforated and split to its outer edge, said tongue bent over itself so as to form the hook substan- 25 tially as described.

In witness whereof I have hereto set my hand this 6th day of January, 1902.

DORA S. DAILY.
